UNITED STATES PATENT OFFICE.

EVERETTE E. ADKINS, OF ALEXANDRIA, SOUTH DAKOTA.

OIL-CAN.

1,247,481.

Specification of Letters Patent. Patented Nov. 20, 1917.

Application filed April 3, 1916. Serial No. 88,588.

To all whom it may concern:

Be it known that I, EVERETTE E. ADKINS, a citizen of the United States of America, and resident of Alexandria, in the county of 5 Hanson and State of South Dakota, have invented certain new and useful Improvements in Oil-Cans, of which the following is a specification.

This invention relates to lubrication and 10 particularly to oil cans.

An object of this invention is to provide novel means for delivering oil under pressure from an oil can so that the flow of the oil is augmented and forced to the proper 15 point for use; the said invention having for its further object the provision of novel means for controlling the discharge of the oil from the can, the said means including a valve which is in such position to the valve 20 seat that when it is moved from engagement with the seat, the passage from the oil can to the discharge tube is unobstructed and this is advantageous for the reason that the full pressure of the air within the oil can 25 may be exerted on the oil and there will be no valve stem or other impediment in the passage.

A still further object of this invention is to provide an oil can, the parts of which are 30 readily disconnected so that the valve and valve seat are accessible for purposes of repairing parts or renewing parts which may become impaired through use and a tight joint, which would obviate or prevent the 35 leakage of oil or air, may be maintained between the said valve and valve seat.

A still further object of this invention is to provide novel means for connecting the oil conduit to the can so that the same may 40 be removed and renewed when any part of the controlling system is impaired.

With the foregoing and other objects in view, the invention consists in the details of construction and in the arrangement and 45 combination of parts to be hereinafter more fully set forth and claimed.

In describing the invention in detail, reference will be had to be accompanying drawings forming part of this specification in 50 which the invention is illustrated by a vertical sectional view of an oil can embodying the invention.

In this drawing, 1 denotes the reservoir or can proper having a cap 2 which may be 55 removed for the purpose of supplying oil to the interior of the can. Near the bottom

of the can, there is a branch pipe 3 having a web 4 constituting a valve seat, the said web having an aperture therein for the passage of air to the can. The valve seat is 60 engaged by a valve 5 threaded in the end of the pipe 3 so that it may be moved with relation to the valve seat of the web 4. A pump barrel 6 forms a continuation of the pipe 3 and air may pass from the pump 65 barrel to the pipe 3 when the valve 5 is unseated, it being understood that when proper pressure has been acquired in the oil can, the valve may be closed to prevent escape of the said air. There is an air pumping piston 9 in the pumping cylinder and a rod 10 extends through the cap 11 of the pump cylinder so that when the piston 9 is reciprocated, air is forced into the can or receptacle 1, and, as stated, when the proper 70 pressure is attained, the valve is closed.

The top of the can has an externally threaded flange 12 which surrounds an opening 13 in the top of the can and a spout or discharge duct 14 has a threaded connection with the flange 12. There is a depending extremity 15 of the member 14 and this extremity projects, in the present embodiment of the invention, downwardly at an angle to the perpendicular and has its receiving end terminating in proximity to the bottom of the receptacle or can. 75

The upper end of the duct 14 is offset and terminates in a vertically disposed cylindrical portion 16, the lower end 17 of which is 80 slightly restricted as compared with the upper portion thereof. The cylindrical portion 16 is externally threaded as at 18 and internally threaded as at 19. The threads on the internal wall are engaged by threads 90 of a valve seat 20, which valve seat has a duct 21 therethrough for the passage of oil and the lower end of said valve seat is engaged by a valve 22 carried by the valve stem 23 which valve stem is slideable in the 100 cylindrical portion of the duct 14 and projects through the reduced end 17 of said cylindrical portion. The valve is held normally seated by a spring 24 which encircles the valve stem and bears against a shoulder 105 25 of the cylindrical portion of the duct 14 and against a shoulder 26 formed on the valve stem. The valve 22 is removably applied to the valve stem and is held in place by a screw 27. The valve may be manipulated or unseated by pressure on the lever 28 which by the pivot 29 is connected to the 110

lower end of the valve stem and said lever is furthermore pivoted to a lug 30 on the external surface of the duct or member 14.

The spout 31 of the oil can has its lower 5 end provided with a flange 32 as shown and this flange rests against a gasket 33 on the outer end of the valve seat. The flange of the spout is held in engagement with the gasket by a ring nut 34 having a 10 flange 35 engaging the flange of the spout and by the threads 36 engaging external threads of the cylindrical portion of the duct or member 14.

By reason of the construction just 15 described, it will be observed that the spout may be expeditiously or conveniently removed from the valve seat and furthermore that said valve seat may be removed by reason of its threaded connection with the 20 cylindrical portion of the duct, and furthermore that the valve stem and valve may be taken from the cylindrical portion by reason of the clearance afforded by the removal of the valve seat.

25 It will be apparent also that the whole of the oil discharging apparatus may be removed from the can by disjointing the parts which are connected to the flange at the top of the oil can.

30 From an inspection of the drawing, it will be apparent that when the valve is drawn

down, free passage is afforded between the valve and valve seat and there is no valve stem or other impediment to the free flow of the oil under the influence of the pressure within the can. 35

I claim—

In an oil can, a receptacle, means for supplying air thereto, an oil discharging means comprising a duct having an extension depending into the receptacle, means for connecting the duct to the oil can, a cylindrical extension forming a continuation of the duct, said cylindrical extension having a reduced lower end, a valve stem slidable 45 therein, means for holding the valve stem normally elevated, a manually operated device for actuating the valve stem, a valve seat removably secured to the upper end of the cylindrical portion and resting on said cylindrical portion, a spout resting on the upper end of the valve seat, and a nut engaging the said cylindrical portion and bearing against the spout for holding it on the seat. 50

In testimony whereof, I hereunto affix my signature in the presence of two witnesses.

EVERETTE E. ADKINS.
